TELEGRAPH SIGNAL REGENERATING APPARATUS

Alder F. Connery, Brooklyn, N. Y., assignor to
The Commercial Cable Company, New York,
N. Y., a corporation of New York

Application July 25, 1936, Serial No. 92,551

5 Claims. (Cl. 178—70)

The present invention relates to signal regenerating apparatus for re-shaping and re-transmitting distorted telegraph signals. More particularly it relates to fork controlled regenerators of the type disclosed in the copending application to Marion H. Woodward, filed July 1, 1936, Ser. No. 88,367.

It is an object of the present invention to provide an improved generator circuit in which the 10 various characteristics of the circuit are readily adjustable.

It is also an object of the invention to provide an improved fork correcting circuit of the type in which corrections of a predetermined duration 15 are applied to the fork when the phase of the fork and of the signal differ from each other by more than a predetermined amount. More particularly, it is an object to provide such a fork correcting circuit in which the above mentioned predetermined duration of the corrections is measured 20 by a reliable, accurate circuit which is readily adjustable and whose time constant is independent of the rapidity with which the corrections recur. Another particular object of the invention is to 25 provide such a fork correcting circuit in which the predetermined amount of phase difference between the signal pulses and the fork contact closures is also measured by a readily adjustable circuit having the desirable characteristics of 30 reliability, accuracy and constancy of time.

The invention may be best understood by reference to the drawings, in which Fig. 1 and Fig. 2, when placed together, form a schematic representation of one preferred form of regenerator in accordance with the present invention. In the drawings, 1 is an incoming cable over which signals are received from a distant transmitter (not shown). It will be assumed that the signals are in the so-called "Submarine Morse" code in which 35 the dots and dashes consist of positive and negative pulses of equal length and in which zero or no current intervals of this same length are used for spaces between letters and words. It will also be assumed that the signals are transmitted at a substantially constant rate as from a 40 tape transmitter.

Relay 2 is a receiving relay of the moving coil type which normally stands with its contact lever midway between its two contacts and is polarized 45 so that it will be actuated to the right by a signal pulse of positive current (a dot) and to the left by a signal pulse of negative current (a dash).

For convenience in reading the drawings, the winding of this relay 2 has been arranged so that 50 a current whose conventional direction through

the winding is from left to right in the drawings will cause the armature of the relay to move in the same direction, that is, from left to right. This same arrangement has been followed with respect to every winding of every polarized relay in both figures of drawings, so that in general the same simple rule may be applied in studying the operations of any of the polarized relays. A current from left to right will move the armature from left to right and vice versa.

Connected to the contacts of receiving relay 2 are the operating windings 103, 104 of the dot and dash locking relays 3 and 4, respectively. These relays 3 and 4 are also provided with biasing windings 203, 204, respectively, through which current is applied to bias the armatures toward the left, as shown in the drawings. Each of these relays is also provided with two locking windings 303, 403, 304 and 404, respectively. These locking windings are so connected in series with the contacts of the relays 3 and 4, that the relays are locked in whichever position they happen to occupy, whenever current is flowing through the relay contacts. Connected to the contacts of the dot and dash locking relays, respectively, (and in series with the above mentioned locking windings) are the operating windings 105, 205 and 106, 206 of dot and dash transmitting relays 5 and 6. These transmitting relays 5 and 6 have no predetermined bias in any particular direction 20 but are provided with semi-locking windings 305, 306 which are so connected to the contacts of the relays themselves that the relays are partially locked in whatever position they happen to be. None of these semi-locking windings, however, 25 produces a strong enough locking bias to prevent the relay from moving to a new position when the appropriate operating winding is energized. The contacts of transmitting relays 5 and 6 are connected to a special ungrounded transmitting 30 battery 7 and the armatures of the relays are connected to the outgoing cable 8 and to the outgoing ground connection, as shown in Fig. 2.

The above described chain of apparatus performs the function of retransmitting to outgoing cable 8 signals whose character is determined by the signals in incoming cable 1. Such a simple repeating equipment, however, is not capable by itself of performing any useful regeneration of the signals. The timing impulses necessary for 40 regeneration are provided by a separate portion of the equipment known as the "timer", shown within the dot and dash lines in Fig. 1. This "timer" is connected to the dot and dash locking and transmitting relays 3, 4, 5 and 6 over wire 45 55

9, in such a way that the operating windings 105, 205, 106 and 206 of the transmitting relays cannot be energized excepting at the moments when negative potential is connected to wire 9 by the 5 timer.

The timer itself has for its principal element a self-driven tuning fork 11 which is arranged to periodically connect wire 9 to a source of negative potential. The normal speed at which this 10 fork operates is primarily determined by the natural resonance period of the fork itself, but is also capable of being slightly varied by means of fork speed rheostat 111, which is connected in the self-energization circuit of the fork. By 15 means of this rheostat the normal running speed of the fork is adjusted to be slightly faster than the average center-hole speed of the incoming signals.

In order to maintain the required synchronism 20 between the fork and the signal, corrector pulse relay 10 is provided. This relay is equipped with two operating windings 110 and 210, as well as one biasing winding 310. The two operating windings 110 and 210 are connected to the same 25 contacts of receiving relay 2 which are used for controlling the re-transmitting equipment, previously described. These windings are so connected that the energization of either one of them will cause the armature of relay 10 to move to the 30 right, the biasing winding being arranged to move this armature to the left. The relative strength of the biasing and operating windings are so chosen that the relay will be rapid not only in operation, but also in its return to normal. 35 Therefore, no matter how rapidly the armature of relay 2 may travel in moving from its left hand contact to its right hand contact or vice versa, relay 10 will not hold over and remain energized, but will release at the moment when the armature of relay 2 leaves one contact and will again 40 re-operate when the armature of relay 2 arrives at the other contact. Thus, it will be seen that relay 10 will operate or move from its left to its right contact at the beginning of each dot or 45 dash transmitted over the incoming cable to receiving relay 2, excepting in the case of a dot which immediately follows another dot, or a dash which immediately follows another dash.

50 Since the incoming signal consists predominantly of dots and dashes, with only a small percentage of zero impulses, and since the occurrence of two dots in succession or two dashes in succession is relatively less frequent than other combinations, it can be seen that relay 10 will be operated by a comparatively large proportion of the signal pulses, thus providing a sufficient number of opportunities for comparing the signal timing with the fork timing.

60 The armature of relay 10 is connected through a two microfarad condenser 410 to a source of positive potential and the left hand contact of this relay is arranged to discharge the condenser through a suitable resistor 510. Thus, upon each 65 operation of relay 10 a brief pulse of positive potential is transmitted out over the right hand contact of the relay. This impulse does not continue as long as the relay continues in the operated state but only occurs for a very short time, 70 each time the relay actually operates. These pulses are used for comparison with a different set of pulses produced by the fork to determine whether or not the timing of the fork and signal differ by more than the tolerated amount.

75 The fork pulses which are used for comparison

with the above described pulses from relay 10, are not derived directly from the fork contacts but from a fork pulse relay 15 which is operated under the control of the fork through a special delay chain 12, 13, 14. This chain determines how much delay will be provided between the closure of the fork contacts and the operation of the fork pulse relay and also independently determines the duration of the operation of this relay. Both of these time intervals can be readily adjusted 10 and will remain exceedingly constant at the value to which they are set.

In this special timing chain, 12 is a vacuum tube whose cathode is connected to a point of zero or neutral potential (designated $\pm$) in the drawings. 15 The screen grid of this tube is connected through a suitable resistor to positive potential. The control grid 412 of this tube is connected through condenser 112 to a source of positive potential—this condenser being shunted by an adjustable 20 high resistance rheostat 212, hereinafter referred to as the "fork-pulse delay rheostat." Grid 412 is also connected through a suitable low resistance 25 312 to a switch 211, which may be connected to either an inner or an outer contact of fork 11. 30 We will assume that the switch is connected as shown in the drawings to an outer contact of the fork, so that negative potential is normally applied to grid 412 except when the fork is attracted toward its inner contacts. Thus, in the 35 condition assumed, and shown in the drawings, the potential of grid 412 will be highly negative with respect to the cathode of tube 12, and condenser 112 will be charged. Anode 512 of this tube is connected to a source of positive potential 40 through the winding of relay 13.

Under the control of the contacts of this relay 45 13 is vacuum tube 14 whose cathode is connected to neutral potential ($\pm$) and whose screen grid is connected through a suitable resistor to positive potential. Control grid 214 of this tube is connected to a source of negative potential through a variable high resistance rheostat 114, hereinafter referred to as the "fork-pulse duration rheostat." When relay 13 is operated, however, this grid 214 becomes also connected to positive potential through a two-microfarad condenser 113. Thus, at the moment of operation 50 of relay 13, control grid 214 becomes strongly positive through the discharge of condenser 113 and then slowly returns to its normal negative potential as this condenser charges through rheostat 114. A suitable discharge resistor 213 is connected to the back contact of relay 13 in such a way as to discharge condenser 55 113 whenever relay 13 returns to its back contact. Anode 314 of this tube is connected through the winding of fork-pulse relay 15 to positive potential, the connection being arranged to pass also through relay 13. The above described chain of 60 apparatus 11, 12, 13, 14 and 15, together with the associated resistors and condensers, serves to cause the operation of fork-pulse relay 15 in response to the vibrations of fork 11. The delay interval between the opening of the outer contact 65 of fork 11 and the operation of relay 15 is adjustable by means of "fork-pulse delay rheostat" 212. The duration of the operation of relay 15 is separately and independently adjustable by means of "fork-pulse duration rheostat" 114. 70

The back contact of relay 15 is connected through a protective resistance 115 to negative potential so that normally, upon the operation of corrector pulse relay 10, condenser 410 will be discharged through this resistance 115. The 75

front contact of relay 16 is connected to the left hand winding of correction pick-up relay 16. Pick-up relay 16 is provided with only one contact in order to make it quick acting. The armature of this relay 16 is connected to a source of positive potential and its single front contact is connected to its own locking winding 116, through the winding of auxiliary correction relay 17 and wire 20 which extends to the bias correcting relay, later to be described. Auxiliary correction relay 17 is provided with two contact levers 117 and 217. Lever 217 is not absolutely essential to the operation of the device but is merely provided to insure reliability. This lever cooperates with its back contact to open the connection of discharge resistor 213 described above, for the purpose of preventing an absolute tie-up in case the front and back contacts of relay 13 become short-circuited by thin filaments of welded metal.

Ordinarily a welded short circuit of this type is only temporary and will disappear after a few openings and closures of the effected contacts. Because of the nature of the present circuit, however, it would be possible for such a short circuit at the point mentioned to tie up the system so that no further contact motions would occur; thus, the difficulty would not clear itself. By the provision of lever 217 and its back contact, such a tie up is prevented. Lever 117 is connected to negative potential and the front contact associated with this lever is connected through an adjustable rheostat 311 to the driving magnet of fork 11. Since this connection does not pass through the outside contact of the fork itself, the closure of lever 117 against its front contact will provide an uninterrupted energization of the fork magnet for the duration of the closure. The characteristics of the fork are such that this energization will not only decrease the amplitude of the fork vibrations but will also slightly slow up the vibrations of the fork. Rheostat 311 enables the intensity of this slowing action to be regulated and is hereafter referred to as the "fork-slowing intensity rheostat." The back contact of lever 117 is used to control a third vacuum tube 18 whose function is to determine the duration of the corrections applied to the fork.

The cathode of tube 18 is connected to neutral potential ($\pm$) while its screen grid is connected through a suitable resistor to positive potential.

The control grid 118 of this tube is connected to a source of positive potential through a condenser 218 which is shunted by a variable high resistance rheostat 318 (referred to as the "fork-slowing duration rheostat"). This grid is also connected through a suitable low resistance 418 to the back contact of lever 117 of the auxiliary correction relay 17. Normally, therefore, the potential on grid 118 is highly negative relatively to its cathode.

Anode 518 of this tube is connected to positive potential through the winding of correction terminating relay 19. This relay 19 is provided with a single front contact which is connected so that upon the operation of relay 19, it short circuits the locking or right hand winding of pick-up relay 16.

In addition to the re-transmitting equipment and the timing equipment described above, there is provided some further apparatus shown on the drawings at the left of Fig. 2 and marked "Bias equipment." Operating windings 125 and 225 of the bias correcting relay 25 are connected in series with windings 110 and 210 of relay 10 so that this relay 25 is operated from the contacts 75 of the receiving relay 2. Because of the reversed

relationship of these windings 125 and 225, however, the bias correcting relay operates in a somewhat different manner from the corrector pulse relay 10—being operated to the left in response to a dot signal and to the right in response to a dash signal. Since relay 25 has no bias winding, and since it is of the two-position type whose armature is incapable of remaining midway between its contacts, the relay will, during no-current or zero signal pulses, remain in the position to which it has last been moved. The armature of this relay 25 is connected to wire 20 which, as shown in Fig. 1, receives a pulse of positive polarity each time the correction pick-up relay operates. The contacts of this relay 25 are connected through its respective locking windings 325 and 425 to two terminals of the automatic bias corrector schematically illustrated below the relay. This automatic bias corrector is of the type fully described and shown in Patent No. 1,929,879 to A. F. Connery.

The function of this automatic bias corrector is to compensate for unsymmetrical conditions of the line circuit or of the transmitting or receiving equipment. This is performed by biasing the receiving relay 2 (by means of an auxiliary winding or its normal receiving winding). The automatic bias corrector acts to change the amount of bias so applied, by small steps between a maximum value of "dash" bias and a maximum value of "dot" bias. In response to a positive pulse upon its left hand terminal (which is produced in response to the occurrence of a correction during a dot signal as hereinafter explained) the automatic bias corrector moves one step in the direction of increased dot bias (or decrease dash bias). In response to a positive pulse on its right hand terminal (which is produced in response to a correction during a dash signal as hereinafter explained) the automatic bias corrector moves one step in the direction of increased dash bias (decreased dot bias). Thus, if the corrections of the fork at a given time are occurring primarily on dot signal pulses, the bias applied to the receiving relay will be cumulatively altered in the dot direction until the symmetry of the signals is so restored that corrections in general take place equally on dots and dashes.

The above detailed description of the apparatus and its interconnections not only provides an adequate disclosure of how to construct the preferred embodiment of the present invention, but almost suffices to make its operation obvious. For completeness, however, a brief description of the operation will be given.

In the timing equipment the self-driving tuning fork 11 has been adjusted so that it is vibrating at a normal speed slightly higher than the average center-hole speed of the incoming signal. Simultaneously, the corrector pulse relay 10 is operating sporadically under the control of the dots and dashes of the signal as received by relay 2. For definiteness in my description, it will be arbitrarily assumed that the desired relation between the fork vibrations and the operations of relay 10 is as follows: the fork just commences to open its left outer contact at the instant which corresponds to the center of an incoming signal pulse as received by relay 2. It will be also arbitrarily assumed that at the present time this desired timing relation is exactly fulfilled.

The instant when fork 11 opens its left hand outer contact will be employed as the reference point from which to compute time for fork 11 as well as for the chain of apparatus 12, 13, 14, 1

directly controlled by this fork 11. The time from this point will be measured in degrees on the basis that one complete cycle of the fork equals 360°. Thus the opening of the left hand outer contact 5 of the fork occurs at fork time 0°.

At the instant of the opening of the above noted contact (that is, at zero degrees) the charge on condenser 112 commences to leak off through rheostat 212. Thus the potential of grid 412 rises exponentially at a rate determined by the "fork-pulse delay rheostat" 212. After a certain interval, the potential of grid 412 is sufficiently high so that the space current of tube 12 operates relay 13. This relay will be assumed to close its make 10 contact at K' degrees of fork time. At the instant when the make contact of relay 13 closes, grid 214 of tube 14 becomes positive through condenser 113. As a result of this positive potential 15 on grid 214, the space current of tube 14 becomes more than sufficiently great to operate the fork-pulse relay 15. This relay 15 therefore closes its make contact at a time only slightly later than K'' ; we will call the moment of this contact closure "fork-time K'' ". The positive potential 20 on grid 214, however, exponentially decreases commencing from the instant when it is applied (from fork time K'') because of the charging of condenser 113 through rheostat 114. After an interval, therefore, the potential of grid 214 becomes sufficiently negative to cause the release of 25 relay 15. The time at which this relay in releasing leaves its make contact will be called fork time C' . This time is accurately adjustable by means of the "fork-pulse duration rheostat" 114.

From the above description it will be seen that the armature of relay 15 remains closed against its make contact during the interval from K'' to C' . Both the duration of this interval and the time of its commencement are accurately and 30 independently adjustable. These time intervals are determined by the charging or discharging rates of condensers through adjustable resistances. The inherent accuracy of such an arrangement is enhanced by the fact that the exponential charging and discharging curves are not used in the vicinity of their asymptotic end-regions (since the negative and positive potentials available for the control grids of tubes 12 and 14 are designed to be far in excess of the values acquired for complete cut-off and for relay 35 operation respectively).

Independently of the above traced train of events, corrector pulse relay 10 is simultaneously operated in response to the incoming signal as 40 received by relay 2. As explained previously, this relay 10 does not operate in response to every pulse but the sporadic operations of this relay when they do occur are precisely timed with respect to the vibrations of fork 11 except for two 45 factors:

- (1) The irregularity of individual signal pulses with respect to the average center-hole speed of the signal.
- (2) The deviation of the fork from its normal 50 time relationship with the center-hole speed of the signals.

So long as the sum of these factors does not exceed a predetermined tolerated amount, correction pick-up relay 16 will not be actuated. This 55 tolerated amount of phase difference between fork 11 and relay 10 is determined by the length of the time interval which has been called K'' . Normally, when the desired relationship between the signal and fork exists, the operations of correction pulse relay 10 will occur shortly before 60

the operations of fork pulse relay 15. In other words relay 10 will deliver its brief surge of current before fork time K'' . In this case, the condenser 410 will discharge through resistance 115 and therefore pick-up relay 16 will not be energized. 5

Assume now that the fork gradually gains in phase with respect to the incoming signal (because of its slightly higher frequency). Finally, the fork will get so far in advance of its proper 10 timing relative to the signal that fork pulse relay 15 will operate before the corrector pulse relay 10. In this case, upon the operation of relay 10 pick-up relay 16 will be operated, locking itself and energizing auxiliary correction relay 17 in an 15 obvious manner. The operation of auxiliary correction relay 17 will apply to the drive magnet of the fork an uninterrupted energization superposed on the regular self-interrupted driving energization. Because of the characteristics of the fork, 20 this uninterrupted energization will slightly slow down the rate of vibration as long as it continues to be applied. The operation of auxiliary correction relay 17 will also permit condenser 218 to discharge through rheostat 318 so that the potential of grid 118 will exponentially rise. After an 25 interval of time determined by the adjustment of rheostat 318, the potential of grid 118 will be sufficiently positive so that the space current of tube 18 will operate relay 19. Finally, the operation of this correction terminating relay 19 will short circuit the locking winding of pick-up relay 16 thus permitting the latter to release. This release of relay 16 causes the release of relay 11, the termination of the fork-slowing current, and 30 the restoration of grid 118 to its normal potential. The restoration of this grid to normal releases relay 19 so that the correction equipment is all in condition for another operation.

In the above description of the operation of the 40 timing equipment there has been described how an unusually retarded signal cooperates with a fork which has slightly advanced in phase to cause a correction which slows down the fork for a predetermined duration of time. The intensity 45 of the slowing or braking current is also predetermined, so that the net result of the correction is to set back the phase of the fork by a definite amount, generally of the order of 15° or 20°. If, in some manner, the fork is so far ahead in phase 50 that it requires more than this amount of correction, a second correction will immediately be applied to it at the next operation of corrector pulse relay 10.

Ordinarily with this system the signals which 55 cause corrections to take place are those signal elements whose effective starting points are unusually retarded with respect to the general average center-hole timing of the incoming message. The unusually retarded signals are in general 60 produced by the transmission of a dot immediately following one or more dash signals or by the transmission of a dash signal immediately following a dot signal. Because of the characteristics of the transmission cable 1, such signals 65 (which require a complete reversal from positive to negative potential or vice versa) are transmitted more slowly than the average signal.

In the absence of any particular bias favoring 70 dot or dash reception, these unusually retarded signals will consist almost equally of dots and dashes. When, however, the receiving relay or transmission line or transmitting equipment presents some sort of dissymmetry, it may occur that dots, for example, are more readily responded to 75

than dashes. In this case, the unusually retarded signals which cause the operation of the correction pick-up relay will predominantly, if not wholly, consist of dashes.

Upon each operation of correction pick-up relay 16, a positive pulse is sent out over wire 20 through one or the other of the contacts of relay 25 to the automatic bias corrector. Relay 25 is, of course, operated to its left hand position by dots 10 and to its right hand position by dashes. Therefore, in the above assumed case in which dots were more favorably received so that the corrections took place predominantly at the time of reception of dashes, the pulses received by the automatic 15 bias corrector will be predominantly on its right hand terminal. This will cause the compensating bias applied to receiving relay 2 to be cumulatively altered in such a direction as to be more favorable for the reception of dashes. Similarly, 20 if the predominating signals are dashes (so that the late signals which cause correction are mostly dots) the automatic bias corrector will be actuated mostly by signals on its left-hand terminal and will therefore cumulatively vary the bias in 25 the direction which is most favorable for dots.

The operation of the re-transmitting equipment itself is very simple. In accordance with the signal received by relay 2 dot or dash locking relay 3 or 4 is operated. Then, at about the center 30 of the signal pulse, a timing impulse is received on wire 9 from the tuning fork 11. This impulse on wire 9 normally locks the dot or dash locking relays in whatever positions they then occupy, and energizes the appropriate windings of relays 5 and 6 to cause these to take up positions corresponding to relays 3 and 4 respectively. When the brief pulse on wire 9 terminates, relays 3 and 4 are again free to move in accordance with the incoming signals but relays 5 and 6 will now 35 remain in their new positions until the arrival 40 of the next pulse on wire 9. Thus, it will be seen that this regenerator equipment determines the character of the pulses transmitted (whether plus, minus, or zero) by means of the character 45 of the incoming signal pulse. This determination is effective at a time which is about the center of the incoming pulse so as to be less affected by distortion. Furthermore, it will be noted that the time at which the outgoing pulses start and end 50 is not determined from the incoming signal but from the timing device. Thus, the signals transmitted out over the outgoing cable 8 are not only re-shaped so as to have square tops but are also re-timed so as to have a uniform, even space from 55 the commencement of each signal element to the commencement of the next one. It will also be noted that these signals are slightly shifted with respect to the incoming signals, since each transmitted pulse commences at approximately the 60 center point of the incoming signal pulse; this however is ordinarily of no consequence.

For best operation, it has been found that the fork speed should be set approximately one cycle per second faster than the average center-hole speed of the incoming signals. The "fork-slowing duration rheostat" should be adjusted so that the correction will last several fork cycles (say 5 or 10). Then, the "fork-slowing intensity rheostat" should be adjusted so that the total 65 phase retardation caused by one correction of the fork is of the order of 15° or 20°. This will mean, of course, that approximately 18 to 24 corrections per second will take place during ordinary transmission.

The "fork-pulse delay rheostat" is now adjusted

to give the desired relation of the timing pulse on wire 9 with respect to the signals received by relay 2. By the inherent operation of the fork correction apparatus the timing relation between fork 11 and the incoming signals will be maintained such that normally fork pulse relay 15 5 will operate slightly later than corrector relay pulse 10. Therefore, since the time of operation of fork pulse relay 15 is K° after the opening of the left center contact of the fork, any 10 variation of the time interval K° will ultimately result in a change in the timing relation between the vibrations of fork 11 and the incoming signal.

The adjustment of "fork pulse duration rheostat" 114 controls the duration of the fork pulse, 15 i. e. the time during which relay 15 remains operative. This time should be longer than the ordinary variations between advanced signals and retarded signals. For example, if some of the signals are transmitted 30° earlier than the 20 average and other signals are transmitted 38° later than the average, the duration of the fork pulse should be at least 68°. On the other hand, the duration of the fork pulse should not be so long as to allow any possibility of extending over 25 into the next following signal pulse, even if this signal pulse happens to be unusually early. For this reason (on the above mentioned assumption of 30° maximum leading distortion and 38° maximum lagging distortion) the fork pulse must be 30 less than 292° in length. Also the total time C° (which is the delay of the fork pulse plus the duration of the fork pulse) should be less than 360°. With the above assumption of signal distortion, and the previous arbitrary assumption 35 that 0° of the fork cycle occurs at the center of the average signal pulse, this will mean that the fork pulse should be less than 142° in length. It will thus be seen that the adjustment of the fork pulse duration rheostat is not at all critical 40 unless the distortions encountered in the signal are unusually severe.

Although the above described embodiment of the invention comprises a fork whose natural speed is higher than the average center-hole 45 speed of the incoming signal, and a correcting system for the fork which acts to delay its phase by a predetermined amount, it is obvious that the converse system can be used in which the fork vibrations are normally slower than the average 50 center-hole rate of the signal. In such a system the correcting signal must be arranged to set forward the phase of the fork (for example, by speeding up its vibrations for a certain length of time).

It will be noted in the above described embodiment the corrections occur when the interval between the opening of the left outer fork contact and the operation of relay 10 becomes greater than the time interval determined by the delay 60 chain 11, 12, 13, 14, 15. It is obvious that without changing the spirit of the invention, the system could be arranged so that the corrections take place when the interval between the fork vibration of the operation of relay 10 becomes 65 less than the interval determined by the delay chain. In general, however, it is a feature of this invention to correct from one side only, i. e. to correct only when the interval between the vibration of the fork and the operation of relay 10 70 becomes unequal in one particular sense to the interval determined by the delay chain.

Also, it should be noted that while the above described embodiment of the invention employs a delay circuit between the fork contact and the 75

fork pulse relay 15 in order to permit the phase of the fork relative to the signal to be varied, it is possible to attain the same result by arranging the delay chain 12, 13, 14, 15 under the control of corrector pulse relay 10 instead of under the control of tuning fork 11 (or both chains together might be used). Either of these arrangements is somewhat superior to the use of a delay chain in wire 9 between the fork and the retransmitting 10 relays because the fork vibrations themselves are employed for timing the regenerator without the interposition of any apparatus.

What I claim is:

1. In a telegraphic signal regenerator a receiving relay, a vibratory timing member, a transmitting relay jointly controlled by said receiving relay and said member, a speed influencing magnet for varying the vibration rate of said member, means for initiating corrections when the asynchronism between the receiving relay and the vibratory member exceeds a certain value, a condenser, a resistor, a space discharge device having a control grid, connections whereby the potential of said condenser is varied by current through said resistor in response to the initiation of a correction by said initiating means, other connections between said discharge device and said condenser such that the space current of said discharge device is varied in response to the potential of said condenser and means for controlling the energization of said magnet under the control of said space current to vary the speed of said member for a predetermined time.

2. A telegraphic signal regenerator comprising a self-driven vibrator, a magnet for influencing the speed thereof, a first means operated responsive to incoming signals, a second means operated in response to the motion of the vibrator, a space discharge tube coupled to said second means, a partially reactive circuit having an adjustable time constant, connections between said space discharge tube and said partially reactive circuit whereby the current through said tube is controlled by said partially reactive circuit to determine a definite time interval and correcting means for controlling the energization of said magnet in response to inequality in one sense by a predetermined amount of the time interval between the operation of said first and second means and the time interval determined by said space discharge tube.

3. A telegraphic signal regenerator comprising a self-driven vibrator, a magnet for influencing the speed thereof, a first device operated responsive to incoming signals, a contact device operated in response to the motion of the vi-

brator, a space discharge tube coupled to said contact device, a partially reactive circuit having an adjustable time constant, connections between said space discharge tube and said partially reactive circuit whereby the current through said tube is controlled by said partially reactive circuit to determine an adjustable time interval and correcting means for energizing said magnet in response to the condition that the time interval between said first device and said contact device is greater than the time interval determined by said space discharge tube and associated circuit.

4. A telegraphic signal regenerator comprising a self-driven vibrator, a magnet for influencing the speed thereof, a first device operated responsive to incoming signals, a second device operated in response to the motion of the vibrator, a space discharge tube, a partially reactive circuit having a predetermined time constant, connections whereby the current through said tube is controlled by said partially reactive circuit to determine a definite time interval, correcting means for controlling the energization of said magnet in response to an inequality of the interval between the operation of said first and second devices, and the time interval determined by said space discharge tube, a second space discharge tube, a second partially reactive circuit having an adjustable time constant, connections whereby the current through the said second tube is controlled by said circuit to determine a second interval and holding means to maintain for the duration of said second time interval the energization of the magnet which is caused by the correcting means.

5. A telegraph signal regenerator comprising a self-driven vibrator, a magnet for influencing the speed thereof, a first device operated in response to incoming signals, a second device operated in response to the motion of the vibrator, corrector means for controlling energization of said magnet in response to a predetermined difference in time between the operation of said first and second device, means for determining said predetermined time difference comprising a space discharge tube coupled to said second device and a partially reactive circuit having an adjustable time constant coupled to said tube, and connections for energizing said corrector means in response to an inequality between the length of said time difference in a predetermined sense and the length of time determined by said adjustable time constant circuit.

ALDER F. CONNERY. 65
